GOLD RECOVERY MACHINE

Walter Everett Mendenhall, Prescott, Ariz., assignor to Mendenhall Gold Concentrator Company, a corporation of Delaware

Application April 8, 1933, Serial No. 665,069

2 Claims. (Cl. 209—437)

This invention relates to a gold recovery machine.

It is well known that gold metal exists in the deposits along numerous river beds and valleys and in the fine sand of placer mining deposits, in the form of fine particles, commonly known as gold flour, and that cannot be effectively recovered by the usual placer mining methods heretofore in use. In the past, many futile efforts have been made to recover this gold flour.

In the Mendenhall Patent No. 1,509,681 there is disclosed an apparatus for recovering the gold flour from the sand or silt. The present invention constitutes an improvement over the apparatus therein shown. The improvement consists principally in the use of a fabric or similar material having interstices or a retarding action with respect to the gold flour upon the bottom of the trays and suitable deflecting means at the ends of the tray to prevent the escape of gold flour during the agitation of the trays and cause such flour to be deflected back into the trays, and in the provision of a tray casing having a convex swinging movement into which water is sprayed to moisten the sand in the trays. The water will wash the gold flour to the bottom of the tray during the convex swinging movement thereof.

The invention comprises the novel structure and combination of parts hereinafter described and more particularly pointed out and defined in the appended claims.

In the accompanying drawings which illustrate a preferred form of this invention and in which similar reference numerals refer to similar features in the different views:

Figure 1 is an elevational view of an apparatus involving this invention;

Figure 2 is a vertical sectional view through the apparatus taken upon the line II—II of Fig. 1;

Figure 3 is a fragmentary sectional view of the trays showing a slight modification thereof;

Figure 4 is an enlarged sectional view taken substantially upon the line IV—IV of Fig. 2;

Figure 5 is an enlarged fragmentary sectional view through a pair of trays;

Figure 6 is a sectional view of the machine illustrating modified features of construction;

Figure 7 is a top plan view of a modified form of end discharge tray; and

Figure 8 is a top plan view of a center discharge tray.

Figure 9 is a fragmentary sectional view taken upon the line IX—IX of Figure 7 looking in the direction of the arrows.

The illustrated embodiment of this invention consists of a supporting base 1 upon which suitable uprights 2 are secured. These uprights are suitably braced to form rigid supports. A casing 3 is suspended from the uprights by means of adjustable links 4 which allow the casing to be swung to and fro or in a form of convex path.

A plurality of trays 5 and 5a in superposed relation are carried by the casing 3 and supported therein by means of metal members 6 at the bottom of the casing which is otherwise open. These metal members have right angled ends 6a which are secured to the sides of the casing. The material passing from the trays falls upon a chute 7 which is attached to the uprights 2 as shown in Fig. 1.

The trays 5 which are end discharge trays are similar in construction and each consists of a square or rectangular frame 8 having a central transverse partition 9 which is slotted as indicated at 10 for a purpose that will later appear. Spaced from the end frame members are transverse floor supporting beams 11 and spaced from the partition 9 are floor supporting beams 12 which are located at a lower elevation than the beams 11. The inwardly directed portions of these beams are provided with rabbets 13 which have curved deflector walls 14 for a purpose that will later appear.

The floor 15 of the tray is supported upon the beams 11 and 12 and extends through the slot 10. This floor consists of some material which has interstices or which resists the travel of gold flour thereover, such as fabric. It has been discovered that canvas or duck has the proper characteristics and for this reason canvas has been illustrated as forming the bottom of each tray. It will be noted that the canvas floor of the tray 5 consists of a medial depressed portion 15a and upwardly sloping portions 15b.

The floor in the tray 5a is differently arranged than the floor in the tray 5. In the tray 5a the floor has a discharge gap at the center and is hence formed in spaced sections 16. It will be noted that each section 16 which also consists of canvas is fastened at its outer end between a pair of frame elements 8a and 8b which form the end of the tray. Within the tray the floor sections 16 are supported upon transverse beams 17 and 18. These beams have curved rabbeted portions 13 similar to those above described and the beams 17 are at a lower elevation than the beams 18 with the result that each floor section has a level depressed portion 16a between 55

the beam 17 and the end of the tray. For it will be noted that the bottoms of rabbets in the beams 17 are substantially in the same horizontal plane with the top of the frame element 8a.

5 As the trays 5a discharge at the center, they may be termed center discharge trays.

In Figure 3 there is illustrated a pair of trays 19 and 20 in which the fabric bottoms 21 are of wavy or corrugated contour shown in exaggerated form. Such a corrugated contour will in some types of flake gold more readily retain the gold flour from movement toward the discharge point of the tray.

With reference to Figure 4 it will be noted 15 that the upper tray 5 is adapted to discharge the coarse material thru the discharge gaps 22 between the beams 11 and the end frame members. This material will fall upon the sections 16 of tray 5a therebeneath and the coarse particles 20 and waste will be discharged thru the discharge gaps 23 and descend upon the bottom of the next tray 5 which discharges the coarse material thru the discharge gaps 22 between the beams 11 and the end frame members. The discharged 25 material will descend upon the bottom tray 5a and be discharged thru the final central gaps 23 and upon the discharge chute 7. Thus the trays 5 and 5a are alternately arranged so that as many such trays may be alternately used as desired; in the present case only four trays are 30 shown, since practice has proven that a greater number are not usually required. More trays might be used to advantage in recovery of unusually fine and flaky gold.

35 In order that the coarse material will travel in the trays as above set forth, the casing 3 is adapted to be swung or oscillated by means of crank discs 24 connected by means of links 25 to the casing 3. The crank discs 24 (only one of which is shown) are secured to the shaft 40 26 which may be driven by a pulley 27 and belt 28 from a motor 29 on the base 1.

Above the trays, there is a sloping sieve or chute 29 having a perforated bottom. The sand 45 containing the gold flour is deposited upon the receiving chute 29. The finer particles pass thru the perforations in the chute while the coarse particles will pass down the chute and not be discharged into the trays.

50 It is desirable to moisten the sand passing thru the machine and for this purpose a fluid tank 30 is attached to the top of the uprights 2. Suitable nozzles 31 attached to the bottom of the tank are adapted to spray a suitable fluid, preferably water, upon the sand upon the chute 29.

During the operation of the apparatus, which is apparent from the foregoing, the fine gold flour will be deposited upon the canvas bottoms of the tray as the coarse and lighter waste particles move upwardly upon the inclined bottoms of the tray during the oscillation of the casing. To effectively cause the best deposit of such gold flour, the bottoms of the tray should be of proper material to impede or prevent the gold flour from moving to the discharge ends of the bottoms of the tray. A fabric such as canvas having interstices in which the gold flour may become embedded and accumulate and that causes the gold flour to adhere thereto and resists the movement of the gold flour thereover has in practice proven a commerical success.

70 During the oscillation of the casing, there is a tendency for the wet flour to be dashed over the ends of the bottoms of the tray, and to prevent this and at the same time to cause the

flour to be deflected back into the tray, the floors of the trays curve upwardly at the discharge gaps as previously set forth. It will be appreciated that the continual spraying of the water as the trays swing to and fro will saturate the sand and wash the gold flour to the bottom, while the coarser material will be discharged. And due to the upward inclinations of the canvas bottoms of the trays, the water will have a component of force acting against the bottoms 10 and this will tend to force the gold flour into the canvas. This swinging movement of the trays in combination with the spraying of the sand with water is an important feature in the recovery of the gold flour.

15 After a sufficient quantity of this gold flour bearing material has been passed thru the apparatus the sand collected in the trays will contain large quantities of gold flour. The trays may be removed and the gold bearing sand removed 20 and the metallic flour may then be brushed from the fabric bottoms. In time these fabric bottoms become saturated with metallic flour and may be removed and treated as the recovered metallic flour.

25 In Figure 6, the parts are similar to the parts shown in Figures 1 and 2 except that the sand receiving chute which is designated by the reference 29a has been modified and the frames of the trays 5 and 5a are slightly modified.

30 Describing first the modified chute 29a, it will be noted that it embodies a lower screen 32 spaced a short distance below the bottom of the main screen or chute 29a. The lower ends of these screens incline downwardly as shown at 33 and 35 transversely extending riffles extend across the inclined portions to intercept nuggets of gold that may exist in the sand and that can not pass thru the perforations in the screens.

35 The end discharge tray 5 has been modified as 40 shown in Figure 7. This modified form of tray which is designated by the reference 35 has the side frame members scarfed as indicated at 36 adjacent the partition 9, to prevent leakage between the trays. It will be noted that these 45 scarfs are bevelled and serve to deflect the water or saturated sand as it tends to pile up or accumulate at the corners where the scarfs exist. These scarfs direct the water upwardly and back into the tray so that it will not escape between 50 the trays.

55 In Figure 8 there is shown a tray 37 similar to the tray 5a that has a center discharge and in which the side frame members are scarfed at their ends as indicated at 38. These scarfs are 55 bevelled for preventing leakage between the trays as above explained.

60 It might be mentioned that the apparatus herein disclosed has gone into commercial use and is the first to succeed in a virtually complete recovery of fine and flaky gold and other valuable metallic substances from gravels, sands and soils.

65 I am aware that many changes may be made and numerous details of construction may be varied through a wide range without departing from the principles of this invention, and I, therefore, do not purpose limiting the patent granted hereon otherwise than necessitated by the prior art.

70 I claim as my invention:

1. In an apparatus of the class described, a casing, means for oscillating said casing in longitudinal directions, a plurality of trays in superposed relation in said casing, said trays having sides with scarfs adjacent the ends, and means 75

for supplying fluid to said trays, said scarfs deflecting the fluid inwardly.

2. In a machine of the class described, a tray comprising a frame, a transverse member in said tray in spaced relation from the end frame member, and having an arcuate rabbet, a second transverse member spaced inwardly from the first

member and having an arcuate rabbet, and a piece of canvas attached to said end frame member and extending over said transverse members and in contact with said arcuate rabbets for the purpose set forth.

WALTER EVERETT MENDENHALL.
